US0D1099191S

(12) **United States Design Patent** (10) Patent No.: **US D1,099,191 S**
(45) Date of Patent: ** Oct. 21, 2025

(54) **DRIVE WHEEL FOR ROBOT**

(71) Applicants: **Hyundai Motor Company**, Seoul (KR); **Kia Corporation**, Seoul (KR)

(72) Inventors: **Soo Kyoung Kang**, Gunpo-si (KR); **Joo Young Chun**, Seoul (KR); **Seok Young Youn**, Seoul (KR); **Hun Keon Ko**, Anyang-si (KR); **Hyeon Jeong An**, Seoul (KR); **Han Wool Choi**, Seongnam-si (KR); **Il Hwan Han**, Seoul (KR); **Dong Jin Hyun**, Suwon-si (KR); **Jae Young Han**, Yongin-si (KR)

(73) Assignees: **Hyundai Motor Company**, Seoul (KR); **Kia Corporation**, Seoul (KR)

(**) Term: **15 Years**

(21) Appl. No.: **35/520,652**

(22) Filed: **Oct. 20, 2023**

(80) **Hague Agreement Data**

Int. Filing Date: **Oct. 20, 2023**

Int. Reg. No.: **DM/233192**

Int. Reg. Date: **Oct. 20, 2023**

Int. Reg. Pub. Date: **Apr. 26, 2024**

(30) **Foreign Application Priority Data**

Apr. 21, 2023 (KR) 30-2023-0015469

(51) **LOC (15) Cl.** **15-99**

(52) **U.S. Cl.**

USPC **D15/199**

(58) **Field of Classification Search**

USPC D15/199; D21/578-583, 621, 622; D34/34; D12/1; D8/375

CPC .. B25J 5/00; B25J 5/007; B25J 11/008; B60B 19/003; G05D 1/0238

See application file for complete search history.

(57) **CLAIM**

The ornamental design for a drive wheel for robot as shown and described.

DESCRIPTION

1. Drive wheel for robot

1.1 : Perspective

1.2 : Front

1.3 : Back

1.4 : Left

1.5: Right

1.6: Top

1.7 : Bottom

(Continued)

Portions of the drive wheel for robot shown in broken lines form no part of the claimed design.
